CARILLON TOY

John H. Lee, Rockford, Ill.

Application February 24, 1945, Serial No. 579,604

8 Claims. (Cl. 46—43)

This invention relates to a new and improved carillon toy.

The principal object of my invention is to provide a toy of attractive appearance and yet simple and relatively inexpensive to manufacture, having chimes preferably of different tones arranged in vertically spaced relation in two spaced hollow columns, in such proximity to the opposite ends of inclined runways that the chimes are struck as marbles roll by gravity off the ends of the runways and drop onto the adjacent upper ends of the runways beneath, thus giving off melodious sounds for the amusement and entertainment of youngsters, the arrangement enabling youngsters to vary the timing of the sounding of the chimes at will, so that their interest is maintained and they do not soon grow tired of the toy.

In the drawing—

Fig. 1 is a front view of a toy made in accordance with my invention, portions of one of the columns being broken away to better illustrate the construction;

Fig. 2 is a top view of the toy, and

Fig. 3 is a horizontal section on the line 3—3 of Fig. 1, showing the parts on a larger scale.

The same reference numerals are applied to corresponding parts in these views.

The toy comprises two spaced hollow columns 4 and 5 having supporting bases 6 and 7, respectively, and top cap pieces 8 and 9, respectively. The walls of the columns 4 and 5 are preferably formed from rectangular pieces of perforated sheet metal 10 bent to approximately C-shape cross-section, as indicated in the section, Fig. 3, the longitudinal edge portions 11 being bent into approximate parallelism, as also appears in the section, to provide spaced vertical supports between which the end portions of a series of chutes 12—17 are arranged to be secured, as by means of screws 18 entered through convenient perforations in the portions 11 of the column pieces 10. Screws 23 entered through perforations in the upper and lower end portions of the columns 10 serve to fasten the columns to reduced portions of the bases 6 and 7 and caps 8 and 9. The pattern of perforation of the pieces 10 is indicated at the lower right hand portion of column 4, and it is apparent that the larger holes 19 are of sufficient size to receive the screws 18. The perforations, besides giving an attractive appearance to the columns 4 and 5, are of advantage from the standpoint that the melodious sounds given off in the striking of the chimes 20 are not muffled by reason of the enclosure of the chimes in the columns. A screw 21 extends through the

center of column 4 and is anchored at its lower and upper ends in the base 6 and cap 8, and forms a support for the three chimes 20 in this column, nuts 22 being threaded on the screw against each chime from the top and bottom to permanently locate the same. A shorter screw 24 is provided in the center of the column 5 for support of the two chimes therein, in a similar manner. The upper end of the screw 24 is fastened to the bottom of the cap 9 by means of a U-shaped sheet metal bracket 25, which straddles the upper end portion of the chute 12, leaving ample room for a marble 26 to be dropped through the center hole 27 in the cap 9 onto the upper end of the chute 12, to start a run through the system of chutes to strike the series of chimes 20 in order, alternating from one column to the other. The lower end of the screw 24 is anchored, as indicated at 28, onto the top of an inverted U-shaped sheet metal bracket 29, which straddles the lower end portion of the chute 17, so as to allow ample room for the marble 26 to run out into the cup 30 provided on the base 7 as a receptacle for the marbles.

Each of the chutes 12—17 has a steeply inclined 25 upwardly projecting end portion 31 on the upper end, by means of which the marble 26 is retained against falling off the end of the chute and is guided into the groove or channel 32 extending lengthwise of the chute. The lower or discharge 30 end of each of the chutes, with the exception of the lowermost chute 17, is beveled off, as at 33, and is located in vertically and laterally spaced relation to the upwardly projecting end portion 31 of the next chute therebeneath, to afford ample 35 clearance therebetween for the passage of a marble 26. The chimes 20 are so located just above the end portions 31 that the marbles in running off the lower ends of the chutes will strike the chimes, and as their momentum is thereby 40 checked the marbles will drop by gravity onto the end portions 31 and be thereby impelled to travel in the opposite direction. The screws 21 and 24 enable accurate adjustment of the chimes 20 relative to the adjacent ends of the chutes associated therewith, so that in the assembling of the device each chime will be properly permanently set for satisfactory operation of the toy.

The operation of the toy is believed to be clear from the foregoing description. A youngster, or 50 youngsters, playing with the toy can, of course, insert a number of marbles 26 in rapid succession in the hole 27, or at stated intervals, to obtain rapid-fire sounding of the chimes or rhythmic ding-donging thereof. As the marbles drop into 55 the cup 30 they can, of course, be retrieved and

used over again, and in that way it is unnecessary to provide very many. The returning of the marbles to the cup eliminates likelihood of their being left on the floor. The variation in the timing of the sounding of the chimes rendered possible with this toy is enough to keep most youngsters interested indefinitely.

It is believed the foregoing description conveys a good understanding of the objects and advantages of my invention. The appended claims have been drawn to cover all legitimate modifications and adaptations.

I claim:

1. A carillon toy comprising spaced substantially vertical carillon towers, inclined chutes mounted at opposite ends in and extending between said towers in vertically spaced relation, alternate chutes sloping toward one end and intermediate chutes sloping toward the other end, chimes mounted in said towers in vertically spaced relation, each chime being large in diameter in relation to the width of the chutes and adapted to serve, independently of said towers, as stop abutments for rolling objects running off the lower ends of said chutes, the lower ends of a number of chutes being disposed in radially spaced proximity to said chimes so that a rolling object rolling off the lower end of a chute will be stopped by striking the adjacent chime and drop down by gravity between the chime and the end of the chute, the upper end portions of a number of chutes being disposed under said chimes so as to catch said rolling objects after they strike the chimes, and one or more freely rolling objects adapted to roll down the runways from one to another and in the course of such movement to strike said chimes alternately in one and then the other of said towers.

2. A carillon toy comprising spaced substantially vertical carillon towers, inclined chutes mounted at opposite ends in and extending between said towers in vertically spaced relation, alternate chutes sloping toward one end and intermediate chutes sloping toward the other end, chimes mounted in said towers in vertically spaced relation adapted to serve as stop abutments for rolling objects running off the lower ends of said chutes, the lower ends of a number of chutes being disposed in radially spaced proximity to said chimes so that a rolling object rolling off the lower end of a chute will be stopped by striking the adjacent chime and drop down by gravity between the chime and the end of the chute, the upper end portions of a number of chutes being disposed under said chimes so as to catch said rolling objects after they strike the chimes, and one or more freely rolling objects adapted to roll down the runways from one to another and in the course of such movement to strike said chimes alternately in one and then the other of said towers, substantially vertically disposed screws in said towers on which said chimes are supported for vertical adjustment relative to the adjacent ends of the chutes.

3. A carillon toy comprising spaced substantially vertical carillon towers, inclined chutes mounted at opposite ends in and extending between said towers in vertically spaced relation, alternate chutes sloping toward one end and intermediate chutes sloping toward the other end, chimes mounted in said towers in vertically spaced relation adapted to serve as stop abutments for rolling objects running off the lower ends of said chutes, the lower ends of a number of chutes being disposed in radially spaced prox-

imity to said chimes so that a rolling object rolling off the lower end of a chute will be stopped by striking the adjacent chime and drop down by gravity between the chime and the end of the chute, the upper end portions of a number of chutes being disposed under said chimes so as to catch said rolling objects after they strike the chimes, one or more freely rolling objects adapted to roll down the runways from one to another and in the course of such movement to strike said chimes alternately in one and then the other of said towers, substantially vertically disposed screws in said towers on which said chimes are supported for vertical adjustment relative to the adjacent ends of the chutes, and nuts adjustably threaded on said screw above and below each chime.

4. A carillon toy comprising spaced substantially vertical carillon towers, inclined chutes mounted at opposite ends in and extending between said towers in vertically spaced relation, alternate chutes sloping toward one end and intermediate chutes sloping toward the other end, chimes mounted in said towers in vertically spaced relation adapted to serve as stop abutments for rolling objects running off the lower ends of said chutes, the lower ends of a number of chutes being disposed in radially spaced proximity to said chimes so that a rolling object rolling off the lower end of a chute will be stopped by striking the adjacent chime and drop down by gravity between the chime and the end of the chute, the upper end portions of a number of chutes being disposed under said chimes so as to catch said rolling objects after they strike the chimes, and one or more freely rolling objects adapted to roll down the runways from one to another and in the course of such movement to strike said chimes alternately in one and then the other of said towers, each tower being of hollow construction, comprising a body member of flexible sheet material bent to substantially C-shaped cross-section to give the towers a substantially cylindrical form to house the chimes, which are of circular form, substantially centrally therein in radially spaced relation to the inside of the tower, the longitudinal edge portions of said sheet material being bent into spaced approximate parallelism on each tower, and said chutes, which are of rectangular form, being disposed with their opposite end portions between said edge portions and suitably secured therebetween.

5. A carillon toy comprising spaced substantially vertical carillon towers, inclined chutes mounted at opposite ends in and extending between said towers in vertically spaced relation, alternate chutes sloping toward one end and intermediate chutes sloping toward the other end, chimes mounted in said towers in vertically spaced relation adapted to serve as stop abutments for rolling objects running off the lower ends of said chutes, the lower ends of a number of chutes being disposed in radially spaced proximity to said chimes so that a rolling object rolling off the lower end of a chute will be stopped by striking the adjacent chime and drop down by gravity between the chime and the end of the chute, the upper end portions of a number of chutes being disposed under said chimes so as to catch said rolling objects after they strike the chimes, one or more freely rolling objects adapted to roll down the runways from one to another and in the course of such movement to strike said chimes alternately in one and then the other

of said towers, each tower being of hollow construction, comprising a body member of flexible sheet material bent to substantially C-shaped cross-section to give the towers a substantially cylindrical form to house the chimes, which are of circular form, substantially centrally therein in radially spaced relation to the inside of the tower, the longitudinal edge portions of said sheet material being bent into spaced approximate parallelism on each tower, and said chutes, which are of rectangular form, being disposed with their opposite end portions between said edge portions and suitably secured therebetween, the sheet material of both body members being perforated substantially uniformly throughout the area thereof to avoid muffling the sound of said chimes, and there being fastening members entered through selected perforations to secure the end portions of said chutes to said towers.

6. A carillon toy comprising spaced substantially vertical carillon towers, inclined chutes mounted at opposite ends in and extending between said towers in vertically spaced relation, alternate chutes sloping toward one end and intermediate chutes sloping toward the other end, chimes mounted in said towers in vertically spaced relation adapted to serve as stop abutments for rolling objects running off the lower ends of said chutes, the lower ends of a number of chutes being disposed in radially spaced proximity to said chimes so that a rolling object rolling off the lower end of a chute will be stopped by striking the adjacent chime and drop down by gravity between the chime and the end of the chute, the upper end portions of a number of chutes being disposed under said chimes so as to catch said rolling objects after they strike the chimes, one or more freely rolling objects adapted to roll down the runways from one to another and in the course of such movement to strike said chimes alternately in one and then the other of said towers, each tower being of hollow construction, comprising a body member of flexible sheet material bent to substantially C-shaped cross-section to give the towers a substantially cylindrical form to house the chimes, which are of circular form, substantially centrally therein in radially spaced relation to the inside of the tower, the longitudinal edge portions of said sheet material being bent into spaced approximate parallelism on each tower, and said chutes, which are of rectangular form, being disposed with their opposite end portions between said edge portions and suitably secured therebetween, the sheet material of both body members being perforated substantially uniformly throughout the area thereof to avoid muffling the sound of said chimes, said towers including tops and bases having reduced portions entered in the upper and lower ends of said body members, respectively, and fastening members entered through selected perforations to secure the tops and bases to said body members.

7. A carillon toy comprising spaced carillon towers having chimes mounted therein in vertically spaced relation, inclined chutes mounted at opposite ends in and extending between said towers in vertically spaced relation, alternate chutes sloping toward one end and intermediate chutes sloping toward the other end, the lower

ends of a number of chutes being disposed in laterally spaced proximity to said chimes so that a rolling object rolling off the lower end of a chute will be stopped by striking the adjacent chime and drop down by gravity between the chime and the end of the chute, the upper end portions of a number of chutes being disposed under said chimes so as to catch said rolling objects after they strike the chimes, one or more freely rolling objects adapted to roll down the runways from one to another and in the course of such movement to strike said chimes alternately in one and then the other of said towers, a base and a top for each of said towers, a vertical threaded rod secured at its ends to the base and top on one of said towers and having the chimes in said tower vertically adjustably mounted thereon, the top on the other tower having a vertical hole provided therein directly over the high end portion of the uppermost chute, the base on the same tower having a receptacle thereon adjacent the lower end of the lowermost chute to receive spent objects, U-shaped members bridging said high end portion of said uppermost chute and the lower end portion of said lowermost chute and fastened to the last mentioned top and base, respectively, and a vertical threaded rod secured at its ends to said U-shaped members and having the remainder of said chimes vertically adjustably mounted thereon.

8. A carillon toy comprising spaced carillon towers having chimes mounted therein in vertically spaced relation, inclined chutes mounted at opposite ends in and extending between said towers in vertically spaced relation, alternate chutes sloping toward one end and intermediate chutes sloping toward the other end, the lower ends of a number of chutes being disposed in laterally spaced proximity to said chimes so that a rolling object rolling off the lower end of a chute will be stopped by striking the adjacent chime and drop down by gravity between the chime and the end of the chute, the upper end portions of a number of chutes being disposed under said chimes so as to catch said rolling objects after they strike the chimes, one or more freely rolling objects adapted to roll down the runways from one to another and in the course of such movement to strike said chimes alternately in one and then the other of said towers, a base and a top for each of said towers, a vertical rod secured at its ends to the base and top on one of said towers and having the chimes in said tower mounted thereon in vertically spaced relation, the top on the other tower having a vertical hole provided therein directly over the high end portion of the uppermost chute, the base on the same tower having a receptacle thereon adjacent the lower end of the lowermost chute to receive spent objects, U-shaped members bridging said high end portion of said uppermost chute and the lower end portion of said lowermost chute and fastened to the last mentioned top and base, respectively, and a vertical rod secured at its ends to said U-shaped members and having the remainder of said chimes mounted thereon in vertically spaced relation.
